CENTER HUNG RADIANT TUBE SUPPORTS

BACKGROUND

Numerous indirectly heated furnaces used in industry are designed with special facilities for controlling the atmosphere in the working chamber. For example, heat-treating furnaces are used in the steel industry for such processes as annealing, normalizing, spheroidizing, hardening, tempering, carburizing, and stress relieving. The atmosphere within the furnace must be controlled in order to obtain desired surface conditions. For these processes, heat-treating furnaces seldom are designed for temperatures in excess of 2,000° F., and generally operate in the 800° F. to the 1,600° F. range. They are usually well insulated and built to minimize air infiltration or loss of special atmospheres.

In heat-treating furnaces of the annealing type, means for controlling the rate of heating and cooling of the workpieces usually are provided. Insulating brick or monolithic linings generally are used in heat-treating furnace construction due to their low heat storage capacity thus permitting rapid heating and cooling of the furnace.

This invention pertains to controlled atmosphere heat-treating furnaces heated by radiant heating tubes. Radiant heating tubes are commonly used for indirect firing, especially where the temperature seldom exceeds the 800° F. to 1,600° F. range. The tubes are supported in place by special brackets or supports. The tubes and the brackets generally are comprised of special alloy materials to reduce the maintenance of these parts to a minimum. Notwithstanding the use of carefully selected alloys for the brackets, as a result of the continual raising and lowering of the temperature gradient through the brackets and other factors, after a period of time they have tended to fail by cracking and in other ways. Failure of a bracket may be disastrous as it may permit a radiant tube to fall or break open and thereby contaminate the atmosphere within the furnace.

One very common application of the radiant tube-type heating is in the radiant tube fired covered-type furnace employed in the heat treating of coils of flat rolled products. In these furnaces the top and four sidewalls comprise a unitary removable cover which can be raised away from the base upon which the coil products are positioned for treatment. Radiant tubes are positioned along at least two sides of the cover and are hung from the center of the cover roof. This invention is directed primarily to the center hung brackets for supporting radiant heating tubes from the roof of furnaces and especially in furnaces wherein the roof and sidewalls comprise a removable cover. My copending application filed of even date entitled RADIANT TUBE SUPPORTS is directed to the brackets for securing the radiant tubes to the sidewalls. In such furnaces, the brackets must secure the radiant heating tubes in a manner in which they will not jar free during the transporting of the cover from one place to another.

Radiant heating tubes usually comprise a U-shaped tube wherein the diameter at the exhaust end is somewhat smaller than at the burner end. At the burner end of the tube, burning fuel-air mixtures are introduced. The exhaust products are removed at the exhaust end of the tube directed to a stack.

Prior art center hung radiant tube support brackets have been complicated structures comprising two elongate facing sections which were bolted together (with clamps located between bolts) around a battery of radiant heating tubes. The complexity of the design has been an unfortunate drawback. The bolting and clamping was a time consuming process. Furthermore, if it was necessary to remove just one tube, the entire support bracket had to be disassembled and reassembled.

It is a feature according to this invention to provide a unitary cast bracket for supporting radiant tubes within heat-treating furnaces of the type described. It is a further feature of this invention to provide a tube bracket, which is more durable, more easily manufactured, less complicated to use, and a

bracket which has the ability to hold radiant tubes in place in the center of a controlled atmosphere furnace when the furnace is being transported from place to place.

BRIEF DESCRIPTION

Briefly, according to this invention, there is provided a unitary cast bracket hung from the roof of an indirectly heated furnace for supporting radiant heating tubes or the like. The bracket comprises an upright channel preferably having spaced stiffening webs therein. Secured to the top of the channel is a fastening means for securing, for example, by bolting, the bracket to the roof of the furnace.

A plurality of paired upper and lower tube support flanges are secured to and extend away from the upright channel. The tube support flanges are arranged to provide a tangential seat for the radial heating tubes. Upper and lower restraining webs are shaped to restrain the movement of the radiant tubes toward and away from the upright channel while accommodating thermal expansion of the tubes and bracket.

The paired upper and lower restraining webs have spaced substantially parallel edges such that the parallel radiant heating tubes having a fixed spatial relation therebetween may be inserted into the restraining flanges.

According to a preferred aspect of this invention, all the webs lie in substantially the same plane, the flanges are all substantially perpendicular to the webs and the face of the upright channel is perpendicular to both the webs and the flanges.

DETAILED DESCRIPTION

Further features and other objects and advantages of this invention will become clear from the following detailed description made with reference to the drawings in which:

FIG. 1 is a pictorial view of a bracket according to a preferred embodiment of this invention.

FIG. 2 is a side view of a bracket according to this invention. Referring now to FIG. 1, the unitary cast bracket comprises an upright elongate channel 1. Preferably, the channel has spaced supporting webs 2 therein. Secured to the top of the channel is a fastening means 3 comprising a horizontal flange 4, supporting webs 5, and fastening flanges 6 and 7, having openings 8 therethrough for receiving a suitable fastener (not shown). Additional supporting webs 9 may extend between the horizontal flange 4 and the uppermost restraining web (discussed hereafter).

A plurality of paired upper 10 and lower 11 support flanges are secured along one edge to the face 12 of the upright channel 1. Typically, brackets according to this invention have five pairs of support flanges. The tube support flanges are arranged to provide a tangential seat for radiant heating tubes. By tangential seat is meant the support flange is tangent to the surface of the radiant heating tubes. In this way, the tubes during most conditions will only contact the bracket along three lines shown in FIG. 1 as dashed lines 15, 16 and 17. Hence, the heat transfer by conduction from the radiant heating tubes to the bracket is slowed.

Lower restraining webs 13 are shaped to restrain the movement of the radiant tube seated on a lower support flange toward and away from the channel while accommodating thermal expansion of the tube and the bracket. Lower restraining webs are secured at their edges to the upright channel and an upper and a lower support flange. Upper restraining webs 14 are shaped to restrain the movement of the radiant tube seated on upper support flanges toward and away from the channel. The upper restraining webs 14, with the exception of the uppermost upper restraining web, are secured at their edges to the upright channel and an upper and a lower support flange. The uppermost upper restraining web is secured at its edges to the upright channel, an upper support flange and horizontal flange 4. The restraining webs (upper or lower) are actually two-part webs separated to permit the support flanges to provide a tangential seat. The edge surfaces 13a and 14a of the restraining webs are curvilinear, preferably

circular having a center of curvature at about the center of curvature of the radiant heating tubes when seated on the tube support flanges. The edge surfaces 13b, 13c, 14b and 14c are preferably parallel to each other.

The channel 1 extends below the lowermost lower support flange. At or near the bottom of the channel a base flange 20 extends away from the face 12. A support web 21 is secured to the lowermost lower support flange, the channel and the base flange. An opening 22 is preferably provided in the support web 21 through which a pipe may be passed to secure two spaced brackets together at the lower ends.

Throughout the specification and the claims, the webs and flanges and channel comprising the bracket according to this invention have been described as secured to each other. It should, of course, be understood that the webs and flanges are not separately formed and joined, but are cast as one unitary member.

Referring now to FIG. 2, it is a side view of brackets according to this invention demonstrating the position of a radiant heating tube (shown in section). The substantially parallel edge surfaces 13b, 13c, 14b and 14c of the restraining webs are shown in FIG. 2, and the manner in which the U-shaped radiant heating tubes 25 may be inserted in the webs is also shown by the dashed lines having arrows at each end.

It should, of course, be clear to one skilled in the art that the edge surfaces of the restraining webs 13b, 13c, 14b and 14c, which have been referred to as substantially parallel, may also be nonparallel, so long as the restraining webs of paired upper and lower support flanges provide spaced parallel pathways for the insertion of the U-shaped combustion tubes into the bracket. The pathways should preferably form an angle of

between 30° and 60° with the plane of the upright channel 1. Having thus defined my invention in detail with the particularity required by Patent Laws, what is desired to have protected by Letters Patent are set forth in the following claims.

I claim:

1. A unitary cast bracket for hanging radiant heating tubes from the roof of an indirectly heated furnace, said bracket comprising:

an upright elongate channel;

means for securing the top of the upright channel to the furnace roof;

a plurality of paired upper and lower tube support flanges secured to and extending away from the upright channel, the said tube support flanges arranged to provide a tangential seat for the radiant tubes;

a plurality upper and lower restraining webs shaped to restrain the movement of radiant tubes toward and away from the channel while accommodating thermal expansion of the tubes and bracket, said restraining webs secured at their edges to the upper and lower support flanges, the restraining webs being shaped to provide parallel pathways for the insertion of U-shaped radiant heating tubes.

2. The bracket according to claim 1 wherein the webs all lie substantially in the same plane and the flanges and the face of the upright channel are substantially perpendicular to said webs.

3. The bracket according to claim 1 wherein the parallel pathways form an angle between 30° and 60° with the upright channel.
